METAL POURING APPARATUS FOR FEEDING
MOLTEN METAL INTO CENTRIFUGAL
MOLDSJohn J. Nolan, Jr., New York, N. Y., assignor to
The Central Foundry Company, New York,
N. Y., a corporation of Maine

Application March 18, 1949, Serial No. 82,166

4 Claims. (Cl. 22—79)

1

The invention relates to metal pouring apparatus for feeding molten metal into centrifugal molds in the casting of pipe and similar objects.

In the manufacture of cast iron soil and pressure pipe by centrifugal casting in rotating metal molds, a problem which has existed for a great many years is one which concerns feeding the molten metal into the mold, (1) rapidly, (2) to distribute the metal uniformly over the rotating surface of the mold, (3) without danger to the foundryman, and (4) so as to produce a good casting, free of laps, blow holes and other surface defects. The general problem is concerned with other objectives as well, but insofar as related to metal pouring, the leading object has been to obtain rapid and uniform distribution of the metal. The problem has been a particularly troublesome one where the metal is cast into unlined or uninsulated metal molds—so-called "chill molds" or "permanent molds," or into molds having very thin coatings which are not truly insulating coatings and which have little insulating effect so that the metal is cooled rapidly and approaches its solidus within a few seconds or so. In this kind of centrifugal casting operation, pipe of the desired characteristics and uniformity can be produced only if advanced foundry techniques are utilized, and considerable skill employed. Even so, trouble is frequently experienced in the pouring of the metal. If all other conditions be perfect, and yet the pouring is not done in just the right manner, satisfactory pipe will not be produced, and the percentage of "rejects" goes up.

Inventors in this art have concerned themselves, heretofore, with elaborate pouring trough arrangements in which the metal is poured from a series of lips, or weirs, spaced throughout the length of the mold, or with troughs which are advanced into the mold to begin the pouring operation at the far end and which are then withdrawn as the metal is being poured, or with apparatus designed theoretically to lay the metal down in the molds in spiral bands, or with special kinds of coatings said to influence the manner in which the metal is distributed over the mold. The number of pouring schemes devised heretofore, and which are still being proposed from time to time, show well the seriousness and importance of this problem.

To begin with, I sought a pouring apparatus which would permit introduction of the molten metal from one end of a rapidly rotating horizontally-arranged mold for casting pipe and the like. It had to do the job with extreme rapidity, for

2

the aim was to distribute the metal uniformly over the surface of the mold from end to end within the relatively short time of approximately 3 seconds (in the case of a 70 or 90 pound pipe). With these and other objects in mind, and after much work and experimentation, I hit upon an idea which seemed to work out much better than anything I had known about or tried before. With reference to the accompanying drawings, I shall now describe what I consider to be the best form of apparatus utilizing my invention.

Fig. 1 is a side elevational view of my apparatus as designed for use in a pipe foundry.

Fig. 2 is a top plan view of the same apparatus.

Fig. 3 is a rear elevational view of the same apparatus, looking at the back of the pouring ladle.

Fig. 4 is an enlarged side elevational view of the pouring ladle and its associated hydraulic control mechanism, with a schematic showing of its operating characteristics.

Fig. 4a is a diagram based on a schematic vertical cross-section of the pouring ladle.

Fig. 5 is a detail view showing, in vertical cross-section, the lip of the pouring ladle and the adjacent trough, or "boot."

Figs. 6 to 9, inclusive, are detail vertical cross-sectional views of the control valve of the hydraulic mechanism, showing several selected positions during a pouring cycle.

Referring to Figs. 1 to 3, my preferred form of apparatus comprises in its general arrangement a ladle 10 supported for tilting movement, a fluid pressure operating device 11 for producing tilting movement of the ladle to discharge molten metal therefrom, and an hydraulic mechanism indicated generally by reference numeral 12, for variably controlling the speed of said tilting movement, the hydraulic mechanism comprising a variable orifice valve 13 operably connected to the ladle 10 as by means of a linkage indicated generally by reference numeral 14, whereby the operating position of the valve changes in response to successive changes in the position of the ladle as it tilts during the metal pouring operation. As the ladle tilts, the molten metal therein is discharged into a suitable pouring trough or "boot" 15 which is arranged to feed the metal into the end of a centrifugal mold 16. The mold is mounted for rotation about a substantially horizontal axis, and for this purpose is arranged in a suitable centrifugal casting machine. As such machines are well known in the centrifugal casting art generally, and in the art of centrifugal casting of metal pipe and similar objects in particular, and inasmuch as the ma-

chine itself forms no part of the present invention, it will not be described in detail here. However, in order that the general arrangement of my apparatus in relation to the mold and to the centrifugal machine may be more fully understood, I have included by way of example a partial showing of the metal feeding end of a machine wherein the mold 16 is provided with flanges 17 (only one of which is shown in the drawings) supported on pairs of aligned rollers 18 fixed to shafts 19 carried by bearing units 20 mounted on the bed frame 21 of the machine. One or both of the roller shafts are driven from a suitable power source.

In my preferred construction the metal pouring apparatus is mounted on a carriage 22 for movement toward and away from the mold so that the end of trough 15 can be run into the end of mold 16 (or into any attachment thereto) during the metal feeding operation. This is the position of the trough and its associated mechanism as shown in Figs. 1 and 2. The carriage has flanged wheels 23 running on tracks 24 mounted on a suitable frame indicated generally by reference numeral 25, as by means of angle irons 26. If desired a vertical adjustment may be provided to assist in aligning the pouring mechanism with the mold. For this purpose I have shown, in angle iron 26, pairs of vertical slots 27 through which extend clamping screws 28 with threaded engagement in the frame. Adjusting screws 29 (Fig. 3) also have threaded engagement with the frame and bear on the under side of the horizontal flanges of angle irons 26. When clamping screws 28 are loosened, adjustment of screws 29 raises or lowers the tracks 24 to bring the carriage and its associated pouring mechanism into the desired alignment with mold 16, after which clamping screws 28 may again be tightened. Movement of the carriage is accomplished by fluid pressure means such as provided by cylinder 30 fixed to the frame 25 as by means of connecting pin 31 in which operates a piston, the piston rod 32 being connected to a bracket 33 fixed to carriage 22. The piston is double acting, and through the operation of a suitable control valve for introduction of fluid to one end or the other of the cylinder, carriage 22 is caused to reciprocate as may be desired. Thus the carriage can be moved to the left as viewed in Figs. 1 and 2 to withdraw pouring trough 15 from the end of mold 16 after the completion of the casting operation. This permits the mold to be removed from the machine without interference with the trough. Conversely, after the mold is placed in the machine and is ready for pouring, the carriage will be moved to the right to bring the trough 15 into the position shown in the drawings.

The side frames of carriage 22 have at the forward end of the carriage suitable means for supporting the ladle 10 for tilting movement. For example, in the construction illustrated, a pair of vertical plates 34 provide bearings for trunnions 35 fixed to a U-shaped frame 36 on which ladle 10 is supported with its laterally extending flanges 37 resting on top thereof. The ladle is held in position in frame 36 by means of clamping fingers 38 attached to laterally extending arms 39 fixed to frame 36. These arms have rounded extensions 40 for pivotal engagement by piston rod brackets 41. One of these brackets is fixed to the piston rod of an air cylinder 11 pivotally secured to the carriage 22 as by having axle shaft 42 pass through a bearing opening in

the end of the cylinder. The other bracket 41 is fixed to the piston rod 41' of an hydraulic cylinder 43 pivotally secured to the carriage at the opposite side of the ladle from air cylinder 11. Air connections 44, 45 lead, through suitable control valves, to a source of air pressure. As air at elevated pressure is admitted to the lower end of cylinder 11, the piston is raised, tilting frame 36, and with it ladle 10, around the axis of trunnions 35.

Hydraulic cylinder 43 forms a part of the hydraulic mechanism 12 to which reference has been made before. This mechanism comprises, in addition to control cylinder 43 and the piston operably connected to the ladle as described, for movement therewith relative to the cylinder during tilting of the ladle, a conduit 46 connecting opposite ends of the cylinder as shown in Fig. 1, through which conduit liquid is required to flow by movement of the piston as the ladle tilts during the metal pouring operation, a variable orifice valve 13 in said conduit, and an operating arm 47 for said valve movable in response to change in the position of the ladle to vary the rate of flow of liquid through valve 13 and thereby produce a corresponding variation in the speed of tilting of the ladle. Movement of operating arm 47 is produced by the linkage 14 previously mentioned. This linkage comprises a strap 48 pivotally secured to operating arm 47 of the valve as by means of stripper bolt 49 passing through a selected one of a series of apertures 50 and through a slot 51 in the valve arm. The upper end of strap 48 is pivotally secured in a similar manner to an arm 52 fixed with respect to the ladle as by attachment to arm 39 of the ladle frame 36.

The hydraulic mechanism may, if desired, further include a by-pass conduit 53 through which liquid can flow when the ladle is being returned to its original position. This by-pass conduit has a check valve 54 therein to limit liquid flow through the by-pass during the metal pouring operation. Thus when the ladle is tilted during pouring, liquid must flow out of the top of cylinder 43 through conduit 46 and back into the bottom of the cylinder. In this part of the operation the liquid cannot flow through the by-pass conduit 53 because of the operation of check valve 54. However when the air pressure is released to lower the ladle to its original position for the succeeding pouring operation, liquid is free to flow from the bottom of cylinder 43 through check valve 54 and by-pass conduit 53 back into the top of the cylinder for quick return action of the ladle. During this return action some of the liquid may also flow through valve 13 and conduit 46, but the by-pass serves to speed up the operation. A water line connection 55 feeding into by-pass conduit 53 provides means for introducing additional water into the hydraulic system whenever needed. A suitable control valve 56 is provided for this purpose.

Pouring trough 15 is fixed to the carriage in position to receive metal discharged from the lip 57 of ladle 10. As shown, ears 58 projecting laterally from the trough rest on top of a U-shaped supporting member 59 fixed to vertical plates 34 of the carriage, the trough being clamped in place by means of suitable fingers 60 or otherwise.

From the foregoing description of the hydraulic control mechanism, it will be understood that the hydraulic control cylinder 43 is operated by the ladle, and that the speed control valve 13 for the control cylinder also is operated by the ladle. This means that the size of the orifice in valve

13 changes progressively during the pouring of the metal from the ladle, thus imposing a varying resistance to the tilting of the ladle. Inasmuch as the ladle is being operated by a fluid pressure device which exerts a substantially constant torque about the tilting axis, the tilting action will be slowed down or speeded up as pouring progresses, depending upon the adjustment of the linkage between the valve and the ladle. In general, for the casting of pipe of uniform wall thickness longitudinally, I have found that improved results are obtained by slowing up the metal pouring operation as it proceeds. If the wall thickness is to vary over the length of the pipe, the linkage can be adjusted so as to produce the desired rate of pour at all times during the pouring cycle.

My apparatus is designed particularly for extremely rapid operation such that the entire pouring cycle may consume as little as 0.06 minute or less—that is, on the order of 3.6 seconds. In casting a 63 pound soil pipe 4 inches in diameter with a wall thickness of $\frac{1}{4}$ inch, I have found that excellent results are obtained if during the first third of the pouring cycle, in respect of time, approximately one-half of the metal in the ladle is poured, with approximately one-third of the total metal being poured in the next one-third, and the remaining one-sixth being poured in the last third of the cycle. I wish it to be distinctly understood that these proportions will vary in accordance with the article to be produced, but in general improved results are obtained if the rate of pouring progressively decreases during pouring, and the apparatus I have described can be adjusted through changing the selected positions of the valve linkage so as to produce the best operation for any particular set of conditions to be met.

In one method of operation of the apparatus, the linkage will be adjusted to the position shown in Fig. 1, which is drawn approximately to scale, and which shows my preferred adjustment for the casting of 63 pound double hub cast iron soil pipe 4 inches in diameter with a wall thickness of $\frac{1}{4}$ inch in an uninsulated metal mold in accordance with the casting method described in my prior United States Patent No. 2,378,723.

The operation of the apparatus will now be described with reference to schematic views Figs. 4 and 4a of the drawings, and to Figs. 6 to 9, detail vertical cross-sectional views of the control valve of the hydraulic mechanism shown in several selected positions during a pouring cycle. We will assume a pouring cycle of $\frac{1}{100}$ of a minute. The position of the ladle and associated mechanism at the beginning of the pouring operation is shown by the full lines in Fig. 4, the level of the metal in the ladle being as indicated in Fig. 4a. The ladle here shown has vertical side walls 61, a flat bottom wall 62 and an arcuate end wall 63, the latter being formed on a curve which has as its center approximately the center of the tilting axis, although this may be varied slightly depending upon the curvature of the lip 57 of the ladle. With this form of ladle, approximately equal increments of metal will be discharged for equal increments of tilting.

$\frac{1}{100}$ of a minute after the beginning of pouring (initiated by turning the control valve of operating air cylinder 11), arms 40 will be in the position shown at 40a in Fig. 4. Through arm 52 and connecting strap 48, the operating arm 47 of control valve 13 will have been moved to the position shown at 47a. At this point the axis of the

conduit 46, i. e. the axis of valve 13, will have been changed slightly due to the change in position of cylinder 43 (to which the conduit is fixed) in following the movement of the ladle about its tilting axis. This change in the valve axis can be seen by comparing the detail views Figs. 6 and 7, Fig. 6 showing the position of the valve and its operating arm 47 at the start of the operation, and Fig. 7 showing the relative positions of these elements $\frac{1}{100}$ of a minute later, that is, after the ladle has tilted through angle A (Fig. 4). During this interval of time, the quantity of metal discharged from the ladle is indicated diagrammatically in Fig. 4a by the area cross-hatched to represent the color brown, and identified as A'. At this point the level of the metal remaining in the ladle is indicated at a. Also at this point the extent to which the valve 13 has been closed is shown in Fig. 7.

Taking the position of the center line of operating arm 47 as indicated in Fig. 6, we see that it is disposed at an angle alpha with respect to the center-line of the valve. This is the zero angle. $\frac{1}{100}$ of a minute later this angle has become beta (Fig. 7). The operating arm 47 therefore has been moved through an angle with respect to the valve of beta minus alpha which, with the settings adopted for the purposes of this specific example, is equal to approximately $33^\circ 30'$. This closes 30 the valve about one-third of the way from its fully open position to its fully closed position.

During the next $\frac{1}{100}$ of a minute the ladle is tilted through an additional angle B with the ladle arms 40 brought to the position indicated at 40b, and the valve operating arm into the position indicated at 47b after rotation through an angle equal to gamma, Fig. 8, minus beta, Fig. 7, or approximately $21^\circ 15'$. During this interval of time the additional quantity of metal which has been discharged from the ladle is indicated diagrammatically in Fig. 4a by the portion cross-hatched to represent the color orange, and identified as B', bringing the level of the metal in the ladle to the line b.

During the final $\frac{1}{100}$ of a minute the ladle is tilted through an additional angle C with the ladle arms 40 brought to the position indicated at 40c, and the valve operating arm into the position indicated at 47c after rotation through an angle equal to delta, Fig. 9, minus gamma, Fig. 8, or approximately $8^\circ 15'$. During this interval of time substantially all of the metal remaining in the ladle will have been discharged, that is, the quantity indicated diagrammatically in Fig. 4a by the unhatched portion identified as C', bringing the surface c of bottom 62 of the ladle into a horizontal position. At this point the valve 13 will be approximately two-thirds closed. The fully closed position of the valve is indicated in Fig. 9 by the line bearing the legend to this effect, and which represents the center line of the valve arm 47.

The entire pouring operation is performed, insofar as the foundryman is concerned, by simply opening the valve of the air operating cylinder; that is to say, the operation is fully automatic. Thus it will be seen that my invention comprises metal pouring apparatus in which the control of the speed of tilting of a ladle is determined by the position of the ladle itself, making the ladle self-regulating in accordance with a predetermined adjustment of the apparatus. More specifically, my apparatus comprises a control cylinder for a ladle supported for tilting movement and a piston in the control cylinder preferably

connected to the ladle for movement therewith relative to the cylinder during tilting of the ladle, a conduit connecting opposite ends of the cylinder and through which liquid is required to flow by the movement of the piston as the ladle tilts during the metal pouring operation, a valve in said conduit, and an operating member for said valve movable in response to change in the position of the ladle to vary the rate of flow of liquid through said valve and thereby produce a corresponding variation in the speed of tilting of the ladle.

The apparatus distributes the metal over the rotating surface of the mold in a substantially uniform layer and with extreme rapidity. This is accomplished without requiring the use of a movable pouring trough. That is, the arrangement is one which permits introduction of the metal to the mold from one end thereof.

I recognize that certain changes might be made in the operative connection between the control valve and the ladle, or in the shape of the ladle, etc., and it should be understood that the terms and expressions which I have employed are used in a descriptive and not a limiting sense, and that I have no intention of excluding such equivalents of the invention described, or of portions thereof, as fall within the purview of the claims.

I claim:

1. Metal pouring apparatus for feeding molten metal into centrifugal molds in the casting of pipe and the like, which comprises a ladle supported for tilting movement about a substantially horizontal axis for the discharging of molten metal therefrom, a member on which the tilting ladle is mounted, a fluid pressure operating device comprising a piston element and a cylinder element, means connecting one of said elements to said member, means connecting the other of said elements to the ladle, and an hydraulic mechanism for variably controlling the speed of said tilting movement, said mechanism comprising a piston element and a cylinder element, means connecting one of said last named elements to said member, means connecting the other of said last named elements to the ladle for movement therewith during tilting of the ladle, a conduit connecting opposite ends of the cylinder of the hydraulic mechanism and through which liquid is required to flow by relative movement between the piston and cylinder thereof as the ladle tilts during the metal pouring operation, a valve in said conduit, an operating member for said valve, and a linkage connecting said operating member to the ladle for moving said valve in response to change in posi-

tion of the ladle to vary the rate of flow of liquid through said valve and thereby produce a corresponding variation in the speed of tilting of the ladle.

5 2. Metal pouring apparatus constructed in accordance with claim 1, in which said valve operating member extends downwardly from the valve so that the rate of pouring progressively decreases during the pouring operation.

10 3. Apparatus constructed in accordance with claim 1, in which said hydraulic mechanism further includes a by-pass conduit connecting opposite elements of the cylinder and through which liquid can flow when the ladle is being returned to its original position, said by-pass conduit having a check valve therein to limit liquid flow through the by-pass during the metal pouring operation.

15 4. Centrifugal casting apparatus comprising a rotary mold, a trough for directing molten metal into one end of said mold and terminating near said end, a tiltable ladle for pouring molten metal into said trough, a member on which said ladle is mounted, a fluid-pressure operating device for applying substantially constant torque to said ladle for tilting the latter to pour said metal into said trough, said operating device comprising a piston element and a cylinder element, means connecting one of said elements to said member, means connecting the other of said elements to said ladle, means for maintaining said trough stationary during pouring of said metal into the mold, an hydraulic mechanism comprising a piston element and a cylinder element, means connecting one of said last named elements to said member, means connecting the other of said last named elements to said ladle, means comprising a valve for controlling passage of liquid from one portion to the other of the last-mentioned cylinder, and linkage means connecting said valve to said ladle to operate said valve for varying the speed at which said ladle is tilted by said operating device in response to changes in the position of said ladle during tilting thereof.
